UNITED STATES PATENT OFFICE.

WILLIAM P. SCHAEFER, OF PHILADELPHIA, PENNSYLVANIA.

DESIGN FOR A SWEAT-BAND.

44,940.

Specification for Design.

Patented Nov. 25, 1913.

Application filed October 8, 1913. Serial No. 794,175. Term of patent 7 years.

To all whom it may concern:

Be it known that I, WILLIAM P. SCHAEFER, a citizen of the United States, residing at Philadelphia, in the county of Philadelphia and State of Pennsylvania, have invented a new, original, and ornamental Design for Sweat-Bands, of which the following is a specification, reference being had to the accompanying drawing, forming part thereof.

Figure 1, is a face view of a sweat band showing my new design. Fig. 2, is a section, on line 2—2 of Fig. 1.

I claim:

The ornamental design for a sweat band, as shown.

In testimony whereof I affix my signature in the presence of two witnesses.

WILLIAM P. SCHAEFER.

Witnesses:

A. V. GROUPE,
S. I. HARPER.
